CLAIM

The ornamental design for a light fixture, as shown and described.

DESCRIPTION

FIG. 1 is a top isometric view of an embodiment of the light fixture.

FIG. 2 is a bottom isometric view of the light fixture of FIG. 1.

FIG. 3 is a front elevation view of the light fixture of FIG. 1.

FIG. 4 is a right side elevation view of the light fixture of FIG. 1.

FIG. 5 is a left side elevation view of the light fixture of FIG. 1.

FIG. 6 is a rear elevation view of the light fixture of FIG. 1.

FIG. 7 is a top plan view of the light fixture of FIG. 1.

FIG. 8 is a bottom plan view of the light fixture of FIG. 1.

FIG. 9 is a top isometric view of another embodiment of the light fixture.

FIG. 10 is a bottom isometric view of the light fixture of FIG. 9.

FIG. 11 is a front elevation view of the light fixture of FIG. 9.

FIG. 12 is a right side elevation view of the light fixture of FIG. 9.

FIG. 13 is a left side elevation view of the light fixture of FIG. 9.

FIG. 14 is a rear elevation view of the light fixture of FIG. 9.

FIG. 15 is a top plan view of the light fixture of FIG. 9.

FIG. 16 is a bottom plan view of the light fixture of FIG. 9.

FIG. 17 is a top isometric view of another embodiment of the light fixture.

FIG. 18 is a bottom isometric view of the light fixture of FIG. 17.

FIG. 19 is a front elevation view of the light fixture of FIG. 17.

FIG. 20 is a right side elevation view of the light fixture of FIG. 17.

FIG. 21 is a left side elevation view of the light fixture of FIG. 17.

FIG. 22 is a rear elevation view of the light fixture of FIG. 17.

FIG. 23 is a top plan view of the light fixture of FIG. 17; and,

FIG. 24 is a bottom plan view of the light fixture of FIG. 17.

The evenly dotted broken lines in the figures illustrate unclaimed features of the light fixture and form no part of

(Continued)

the claimed design. The dash-dot-dot-dash broken lines in the figures define boundary lines that form no part of the claimed design.
